UNITED STATES PATENT OFFICE

148,625

DESIGN FOR A RUG

Walter P. Kansteiner, Columbus, Tex.

Application January 31, 1947, Serial No. 136,603

Term of patent 14 years

(Cl. D92—21)

To all whom it may concern:

Be it known that I, Walter P. Kansteiner, a citizen of the United States of America, residing at Columbus, in the county of Colorado and State of Texas, have invented a new, original, and ornamental Design for a Rug, of which the following is a specification, reference being had to the accompanying drawing, forming part thereof.

The figure is a plan view of a portion of a rug, showing my new design. The remaining area of the rug repeats the design unit shown in proper relation to complete a rug having four identical corners.

I claim:

The ornamental design for a rug, as shown and described.

WALTER P. KANSTEINER.
